SPRINKLER ATTACHMENT FOR FLATIRONS

Arthur V. Jackson and Augusta R. Jackson,
Hercules, Calif.

Application June 20, 1934, Serial No. 731,402

8 Claims. (Cl. 68—26)

This invention relates to a sprinkler attachment for flat irons.

In the common practice of ironing clothes, starched pieces must be sprinkled and rolled several hours before ironing, usually the night before. If the quantity of clothes prepared for ironing is left in a rolled, dampened condition for too long a period of time, mildewed clothing will be the result. This often happens if the housewife is called to other duties or unavoidably delays her ironing. In warm or dry weather large starched pieces, such as curtains, table linens, or doilies with light laces or sheer material, dry before it is possible to finish ironing the whole piece. The common practice for correcting this is dampening dried parts with a wet sponge or cloth. While ironing starched pieces wrinkles are occasionally ironed into the cloth which have to be re-dampened to be removed. All of this requires additional work and time, that is, trips to the kitchen sink or a bowl of water within reach.

The object of the present invention is to provide a sprinkler for flat irons and the like whereby the clothing may be sprinkled at the time of ironing, thereby eliminating the necessity of sprinkling and rolling the clothes prior to the time of ironing; to provide a sprinkling device which may be attached to irons of different makes; to provide a spray nozzle which is adjustable to direct the spray over any area desired and which is capable of sprinkling wide or narrow surfaces as conditions may require; to provide means for catching and absorbing any drips of water leaking from the nozzle, and further, to provide a valve mechanism which can be manipulated by the mere pressure of the thumb while ironing and whereby the delivery of water to the nozzle is instantly and readily regulated.

The invention is shown by way of illustration in the accompanying drawing, in which—

Fig. 1 is a side elevation of a standard form of flat iron showing the sprinkler attached thereto.

Fig. 2 is a plan view of the sprinkler attachment, said view being partially in section.

Fig. 3 is an end view of the sprinkler attachment, said view being partially in section.

Fig. 4 is a side elevation of the sprinkler attachment partially in section.

Fig. 5 is a sectional view of the sprinkler nozzle.

Fig. 6 is a front view of the sprinkler nozzle.

Referring to the drawing in detail, and particularly Figs. 1 to 3, A indicates a standard form of flat iron, B the handle by which the iron is grasped when in use, and 2 the arms securing the handle to the iron. Secured to the front arm of the han-

dle by means of a clamping screw 3 is a U-shaped bracket 4 and adjustably secured to one side of the bracket by a bolt and nut 5 is a housing generally indicated at C, which serves two functions, first that of a support for a spray nozzle generally indicated at D, and secondly as a support for a valve whereby the flow of water to the spray nozzle is regulated.

The spray nozzle consists of a tube 6 secured in the forward end of the housing. This tube terminates in a spherical member 7, see Fig. 5, which is substantially enclosed by a spray head 8. This head carries a diaphragm or plate 9 which is perforated as indicated at 10. The head is rotatable on the spherical member and is also tiltable thereon and as the perforations are arranged in row formation the head can be rotated to position the perforations vertically or horizontally so as to spray narrow or wide surfaces, and by tilting the head the spray may be directed in any direction 20 required.

Water to supply the spray nozzle is delivered by a rubber or other flexible tube, such as indicated at 11. The rubber tube extends through the housing C and is connected to the end of the tube 6 in any suitable manner. The flow of water through the tube is stopped by pinching the tube by means of a spring arm 12, forming a continuation of the coil spring 13, one end of which is anchored or secured in the housing. The opposite end of the arm extends through a slot 14 formed in one side of the housing and is provided with a pusher head or button 15, whereby the pinch arm which functions as a valve may be actuated.

The iron shown in the present instance is electrically operated and is provided with a socket 16. When the iron is to be used a plug is inserted and this is provided with an extension cord not shown. The rubber tubing supplying the water to the nozzle should preferably be attached to the extension cord and it may be extended to any suitable source of supply, such as an elevated tank or the like. By attaching the tubing to the extension cord it will move freely with the same 40 when the iron is in use and as such will not interfere with the work. When the iron is in use, it will be grasped by the handle B and as the button 15 is disposed at one side thereof and directly beneath the thumb of the operator, it can be 50 quickly and readily depressed whenever a spray is desired. When depressing the button the arm 12 is moved away from the tubing and as such permits it to spread or open so that water will flow to the nozzle to be sprayed in a forward di- 55

rection by the same, the exact direction of the spray being controlled by adjusting the head 8 so as to throw the spray as required. If a narrow row ribbon is being ironed, the head may be rotated so that the perforations 10 will assume a vertical position, and if wide surfaces are to be sprinkled the head will be rotated so that the perforations will assume a horizontal position. Again, by tilting the head a spray may be directed 10 to one side or another or forward as occasion will demand; the adjustment of the head of the spray nozzle being quickly and easily accomplished by merely grasping the head and rotating or tilting it.

15 The valve mechanism employed is of the pinched type as the water is shut off by the pinching action of the arm 12 against the tube, as clearly shown in Fig. 3; the flow of water through the tube being regulated by merely depressing the 20 arm through means of the button and if large pieces are being worked upon and a continuous spray is desired the button may be depressed to such an extent that the arm 12 will move out through the bottom of the slot 14, see Fig. 4, where 25 it may be secured in open position by swinging the arm into engagement with the notch 14a, thus relieving the operation of applying pressure to the button at all times.

In operation it has been found that one or more 30 drips may escape from the spray nozzle when the water supply is shut off. Such drips are fairly large and tend to form spots which are too damp. To remove or dry out such a wet spot with a hot iron will sometimes result in scorching the 35 surrounding cloth. To avoid such annoyance and damage a drip pan is employed and is generally indicated at E. It is detachably secured to the bracket 4 by providing a forwardly extending tongue 17. The pan is cup-shaped, as shown in 40 Fig. 4, and is provided with an extension 17a. It telescopes with relation to the tongue 17 so that it can be quickly applied or removed. A pad 45 of any suitable absorbing material, such as shown at 18, is placed in the pan or cup and retained therein by a perforated plate 19 which is mounted loosely within the cup so that it may be pressed downwardly against the absorbent material. The plate 19 is preferably retained against removal from the cup as by lugs bent from the upper edge 50 of the cup as shown in Fig. 4, and in this manner the absorbent material is retained against accidental removal. Any drips which escape from the nozzle will strike the perforated plate and will drain through the same to be absorbed by the 55 pad 18, and if the pad becomes saturated it is a simple matter to release it from the tongue 17 and then to carry it to the kitchen sink and merely apply pressure on the perforated plate. Such pressure squeezes the pad 18 and releases the 60 excess water content. The drip pan can then be re-applied and will function as described. In fact, all of the mechanism comprising the sprinkler attachment is exceedingly simple in construction and operation and all adjustments and operations are quickly and easily accomplished, and 65 no interference with the main work in hand, to wit, that of ironing, is encountered.

Flat irons, such as shown in Fig. 1, are made by numerous manufacturers and are of varying 70 sizes and shapes. The arms 2 supporting the handle B may also vary to some extent and adjustment of the housing with relation to the attaching bracket 4 is thus important, as it permits the housing to assume a substantially horizontal 75 position regardless of the shape or angle of the

iron 2. The tongue 17 is bendable and so is the tube 6 so it can be seen that all adjustments required are easily taken care of, and while these and other features have been more or less specifically described and illustrated, we wish it understood that various changes may be resorted to within the scope of the appended claims. Similarly, that the materials and finish of the several parts employed may be such as the manufacturer may decide, or varying conditions or uses may 10 demand.

Having thus described our invention, what we claim and desire to secure by Letters Patent is:—

1. In a device of the character described a 15 housing, a spray nozzle secured thereto, a flexible tubing extending through the housing and connected with the nozzle to supply water thereto, a spring in the housing and an arm actuated by the spring and extending crosswise of the housing and engageable with the tube to pinch it and 20 shut off the flow of water to the nozzle, and a button carried by the spring actuated arm whereby the arm is depressed and moved away from the flexible tube to permit the tube to expand and water to flow to the nozzle. 25

2. In a device of the character described a 30 housing, a spray nozzle secured thereto, a flexible tubing extending through the housing and connected with the nozzle to supply water thereto, a helical spring anchored at one end in the housing, an arm forming an extension of said spring and extending crosswise of the housing and engageable with the tube to pinch it and 35 shut off the flow of water to the nozzle, and a button carried by the spring actuated arm whereby the arm is depressed and moved away from the flexible tube to permit the tube to expand and water to flow to the nozzle. 40

3. In a device of the character described a 45 housing, a spray nozzle secured thereto, a flexible tubing extending through the housing and connected with the nozzle to supply water thereto, a helical spring anchored at one end in the housing, an arm forming an extension of said spring and extending crosswise of the housing and engageable with the tube to pinch it and 50 shut off the flow of water to the nozzle, a button carried by the spring actuated arm whereby the arm is depressed and moved away from the flexible tube to permit the tube to expand and water to flow to the nozzle, and means for retaining the spring actuated arm in depressed position. 55

4. In a device of the character described a 60 bracket adapted to be clamped to the handle of a flat iron, a tongue projecting forwardly from the bracket, a drip collector comprising a pan to contain a water absorbing material, means for detachably securing the pan to the tongue, a perforated cover plate on the pan resting on top of the water absorbing material, means retaining the cover plate against removal from the pan, said cover plate being smaller in diameter than the interior of the pan to permit the cover plate to be depressed against the water absorbing material to express excess water therefrom. 65

5. In a device of the character described a 70 spray nozzle comprising a tube terminating in a spherical member, a head rotatably and tiltably mounted on the spherical member, and a plate secured in the head in front of the spherical member, said plate having a relatively narrow band of spray orifices formed therein whereby the area to be sprayed may be controlled by rotating and tilting the head. 75

6. An attachment for a flat iron handle comprising a bracket adapted to be secured to the

handle, a housing carried by the bracket, a spray nozzle carried by the housing, a tube extending through the housing and connected with the nozzle to supply water thereto, and a valve carried by the housing cooperating with the tube to control the flow of water.

7. An attachment for a flat iron handle comprising a bracket adapted to be secured to the handle, a housing carried by the bracket, a spray nozzle carried by the housing, a tube extending through the housing and connected with the nozzle to supply water thereto, and a valve carried by the housing cooperating with the tube to con-

trol the flow of water, said valve being normally spring-closed and means on the housing co-acting with the valve to maintain it in an open position.

8. In combination with a sprinkler attachment for flat irons comprising a sprinkler nozzle, a drip pan positioned beneath said nozzle, an absorbent material in said drip pan, and means carried by the pan for squeezing excess moisture from the absorbent material without removing the material from the pan.
